UNITED STATES PATENT OFFICE.

BALERA J. AURAND, OF LAPORTE, INDIANA.

HINGE.

No. 916,648.

Specification of Letters Patent.

Patented March 30, 1909.

Application filed January 2, 1908. Serial No. 408,873.

To all whom it may concern:

Be it known that I, BALERA J. AURAND, a citizen of the United States, residing at Laporte, in the county of Laporte and State of Indiana, have invented a certain new and useful Improvement in Hinges, of which the following is a specification.

My invention relates to a combined hinge and support. I have shown it as applied 10 to a couch cover, though it might be applied in many other ways and to many other devices. This application of it is illustrated in the accompanying drawings, wherein—

Figure 1 is a section through a couch, 15 case or box; Fig. 2, a plan view of the same showing the hinge in position with the cover removed, Fig. 3, an enlarged detail of the hinge. Fig. 4, an end view of a box and lid with a modified form of hinge on the outside, parts shown in two positions.

Like parts are indicated by the same letter in all the figures.

A is the bottom, B, B the sides, and C the lid, top or cover of the box or case.

D shows upholstering which may be applied to the top of the cover or lid to make 25 a couch.

E is a body portion or sheet of metal of any desired shape. I have here shown it as 30 U-shape. It is provided with holes E¹ E¹ whereby it may be secured by the screws E² to the inside of the end F of the box or case. The upper portion of the metal plate E is provided with the arc shaped slot E³ 35 and projecting upwardly therefrom is the vertical slot E⁴.

G is the horizontal portion and G¹ the vertical portion of an angle iron which is provided with the holes G² G² through which 40 are introduced the screws G³ whereby the horizontal portion of the angle iron is secured on the bottom of the lid C.

The shanks of two bolts J, J, are passed 45 through the slots E³ and E⁴ respectively.

Washers J¹ J¹ are put upon said bolts between the upwardly projecting portion of 50 the plate E and the plate G¹, and the ends of the bolts pass through holes in the plate G¹. The parts are then held in this position by

55 the nuts J² J².

Referring to Fig. 1, the parts will be seen in the position of rest with the lid or cover down. If now, one desires to open the lid it can be thrown in the vertical position 55 shown in dotted lines. It will be observed that the angle-iron, being rigidly secured to

the lid C, will turn with the lid, but as it turns, the bolts J, J begin to travel in their respective slots, and as the motion is continued a time will come when they will be 60 in a vertical line, the upper at the top of the vertical slot, the other immediately below it, and the turning motion of the lid being continued, they will assume the position shown in dotted lines in Fig. 1, where 65 one of these bolts has traveled the entire length of the arc shaped slot and the other is partly up the vertical slot. The lid is then in the position shown in dotted lines. This movement is accomplished entirely 70 within the vertical planes which bound the box or case. In other words, it is not necessary to move the case out from the wall against which it may be standing in order to raise the lid. At the same time the lid 75 is securely held in its vertical position. It can only be restored to its original position by a peculiar upward motion or by special pressure. At the same time it will be observed that in making this motion the lid 80 does not descend into the case. The upper portion of the metal part E projects above the top of the case and along side of the lid.

It will be noted that I am simply showing this device diagrammatically and that the 85 idea can be applied in many different ways and for many different uses.

The modified form of Fig. 4 comprises two slots only, differently situated with relation to each other and not intercepting. 90 These slots are numbered respectively K and L. Each is associated with a screw bolt lettered respectively M N. These bolts are in fixed position on one member, as, for example on the lid of the box, and they pass 95 through their respective slots and are held in position because the head overlies the outer surface of the sheet metal body E. When the lid is moving into the position shown in dotted lines, the movable connections operate as indicated, the two bolts first traveling 100 upwardly in their respective slots and the top bolt then descending in its slot.

The use and operation of my invention have already been sufficiently disclosed. As 105 previously stated, it can be applied in many different ways and for many different uses. It is a combined support and hinge, being in fact, the device which serves as a hinge and at the same time holds the hinged object 110 securely in position at the end of its movement. It also permits the lid to move with-

out going beyond the vertical plane of the back of the box or case or other object to which the hinged lid or other part is attached. It could be used in connection with trunks, trunk trays, and all kinds of doors, lids, etc. It could also be used for such doors as stand in a vertical position. It would only be necessary to modify its form to suit the different uses to which it would 10 be put.

The operation of the device shown in Fig. 4 is easily understood. The parts are so arranged that the top is tilted backward, but, of course, it can be brought to any position 15 by determining the length of the small slot

L. In any event the lid moves without projecting very far over and is held in fixed position when at the end of its movement.

I claim:

In a combined hinge and support, the 20 combination of a fixed part having an arc-shaped slot and a vertical slot connected therewith and above the same, with a movable part having two securing devices which project through said slots respectively.

BALERA J. AURAND.
